HAND TACKER

Frank S. Boroughs, Elmhurst, N. Y., assignor to
Arrow Fastener Co., Inc., Brooklyn, N. Y., a
corporation of New York

Application March 8, 1951, Serial No. 214,513

14 Claims. (CL 1—49)

1

This invention relates to hand staplers or tackers.

One object of this invention is to improve the tacker disclosed in my copending application Serial No. 42,760, filed on August 6, 1948, and issued as U. S. Letters Patent No. 2,617,096 on November 11, 1952. In said copending application there is disclosed a tacker comprising a body, a handle pivoted to the body, a spring pressed plunger carrying a driver blade, a trigger engaging the plunger, and means on the handle to rotate the trigger when the handle is pressed toward the body, for lifting the plunger and compressing its spring. In said copending application, when the plunger reached a certain predetermined point and the spring was pressed to a predetermined degree, the trigger was released permitting the plunger to be moved downwardly by the pressed spring, and bringing the trigger down with it.

In accordance with the present invention there is provided a hand tacker comprising a body, a handle pivoted thereto, and a spring pressed plunger carrying a driver blade. As the handle is pressed it operates a trigger for lifting the plunger. When the plunger is lifted to a predetermined degree and the spring is pressed to a predetermined pressure, the trigger releases the plunger permitting the plunger to descend under the impact of the pressed spring, but unlike the previous application, the trigger remains up and does not descend with the plunger.

Another object of this invention is to provide a highly improved means for lifting the plunger and compressing the spring and then letting go of the plunger when it reaches a certain height and predetermined spring pressure.

Another object of this invention is to provide in a tacker of the character described, a spring pressed plunger, a trigger for lifting the plunger, including arms disposed on both sides of the plunger, a handle pivoted to the tacker body, and a link pivoted to the handle and also pivoted to the trigger, said trigger having a pin and slot connection relative to the body.

A further object of this invention is to provide a tacker of the character described comprising a tacker body, a handle pivoted to the body, spring means for normally raising the handle, a plunger slidably mounted in the body, spring means for pressing the plunger downwardly, a trigger formed with a slot, a pivot pin on the body passing through the slot, a link interconnecting the handle with the rear end of the lever, and a spring for normally pressing the lower end of the link

forwardly to urge the trigger to slide forwardly so that the rear end of the slot receives the pin, and means on the plunger engageable by the front end of the trigger when the handle is pressed downwardly, the construction being such that when the plunger is raised by depressing the handle a predetermined height, further pressure of the handle downwardly towards the body will cause the trigger to suddenly snap back and release the plunger, so that the plunger spring will cause the plunger to descend and drive a staple, leaving the forward end of the trigger in raised position, the construction being such furthermore that after the plunger descends, release of the handle will permit the handle to be raised, pulling up the link and permitting the spring on the link to press the trigger forwardly to again bring the pin to the rear end of the slot. The front end of the trigger is curved so as to permit the trigger to bypass the engaging means on the plunger as the handle is raised.

A still further object of this invention is to provide a strong, rugged and durable tacker of the character described, which shall be relatively inexpensive to manufacture, easy to manipulate, sure and positive in operation, and yet practical and efficient to a high degree.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

Fig. 1 is a front elevational view of a tacker embodying the invention with parts broken away, and in cross-section, and the plunger in its "down" position;

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 1;

Fig. 5 is a view similar to Fig. 1 but showing the handle pressed to a point just before the plunger is released;

Fig. 6 is a partial view similar to Fig. 5 but showing the handle fully depressed and the plunger released and moved downwardly by the spring;

Fig. 7 is a cross-sectional view taken on line 7—7 of Fig. 1; and

Fig. 8 is a partial side elevational view of the device embodying the invention with parts broken away.

Referring now in detail to the drawing, 10 designates a tacker embodying the invention. The same comprises generally of a body 11, a depressable handle 12 pivoted thereto about pivot pin 13, a bracket 14 attached to the underside of the handle, a link 15 pivoted to the bracket as on pivot pin 16, a trigger 17 pivoted at its rear end to the lower end of the link as on pivot pin 18, and a plunger 19 adapted to be raised and abruptly released by the trigger when the handle is depressed, as will appear hereinafter.

The body 11 comprises a pair of similar symmetrically disposed body portions 20. The body portions 20 comprise parallel side walls 21 having lower end edges 21a. Extending inwardly from the side walls 21 are inwardly curved flanges 22 forming a hand hole 23. The flanges 22 have mutually contacting edges 22a as the meeting plane between said members 20. The side walls 21 have top inwardly curved portions 24 having meeting edges 24a in the plane of the edges 22a. The flanges 24 run along the top of the body members 11 and are curved downwardly at their rear ends as at 25, and curved upwardly at their front end as at 26. The rear ends of the body portions are cut away as at 27 for the purpose hereinafter appearing. The side walls 21 have top edges 28 extending forwardly from the upper ends of the flanges 26. At the forward end of edges 28 are downwardly and forwardly curved edges 29 from which extend downwardly, straight edges 30.

Extending from the lower ends of edges 30 are horizontal shoulders 31. At the forward ends of the side walls 21 are outwardly pressed U-shaped walls 32 having forward edges 33. The upper ends of the edges 33 extend to the rear ends of the edges 31. Extending forwardly from the lower ends of edges 33 are horizontal edges 34. Extending downwardly from the forward ends of the horizontal edges 34 are front edges 35 which extend down to the underedges 21a.

The side walls 21 (Fig. 8) are formed with horizontal slots 36 adjacent the front edges 35 and disposed below the outwardly pressed portions 32. Said side walls 21 are also formed with horizontal slots 38 (Fig. 4) disposed adjacent the edges 30 and above the outwardly pressed portions 32.

Body portions 20 are interconnected by means of a rear rivet 40 passing through suitable openings in the side walls 21 and located adjacent the rear end of the body. Said body portions are also interconnected by a transverse pin 41 (Figs. 2 and 8) located at the centers of the rear curved shoulders of the U-shaped outwardly pressed portions 32.

At the upper front corners of the body portions 20 are suitable openings to carry the transverse pivot pin or rivet 13. Fitted over the front of the body 20 is a front cover member 45. Said front cover member 45 comprises a front wall 46 and parallel side walls 47. The side walls 47 are formed with suitable bearing openings through which the pivot pin 13 passes. Said side walls 47 and the side walls 21 of the body members 20 are formed with suitable registering openings to receive therethrough a bolt or screw 48. When the bolt 48 is removed the front cover member 45 may be swung forwardly and upwardly. The

front wall 46 has a forwardly recessed or pressed vertical portion 50 for the purpose hereinafter appearing.

Mounted on and between the side walls 21 is a bottom stop member 51 having outwardly extending lugs 52 received within the slots 36. At its forward end, bottom stop 51 has a slot or groove 53 for the purpose hereinafter appearing. Riveted to the top of the bottom stop 51 by means of rivet 54 is a rubber-like shock absorber 55.

Mounted on and between the side walls 21 of the body members 20 is a top stop 57 having lugs 58 received in the slots 38. Slidably mounted for reciprocation between the body members 20 and located between the shock absorbing disc 55 and the top stop 57 is the plunger 19. Said plunger 19 comprises a bottom wall 60 (Fig. 4), a front wall 61 extending upwardly therefrom, a rear wall 62 extending upwardly therefrom and parallel to the front wall, and side walls 63 extending upwardly from the bottom wall and parallel to each other.

Attached to the front wall 61 by means of rivet 64 is a driver blade 65 which moves through the groove 53 in the bottom stop 51. The head of the rivet 64 moves through the outwardly recessed portion 50 of the front wall 46 of cover or nose piece 45. At the upper end of the front wall 61 is a forwardly pressed portion 66 (Fig. 5) to contact the inner surface of the front wall 46 above the recessed portion 50. The plunger is thus guided up and down as it is moved in the manner hereinafter appearing.

Disposed within the plunger and between the bottom wall 60 and the top stop 57 is a coil compression spring 67 which normally presses the plunger down against the shock absorber 55. Pressed outwardly from the side walls 63 of the plunger are raised lugs 68. The lugs 68 have rearwardly and upwardly inclined underedges 69, and rear vertical edges 70.

It will now be understood that when the plunger 19 is raised the spring 67 will be compressed, and when the plunger is released the compressed spring will cause the plunger to descend forcefully to drive a staple, as will appear hereinafter.

Disposed within the bottom of the body and between the side walls 21 is a staple magazine 71. The staple magazine 71 may be similar to the staple magazine shown in my copending application Serial No. 42,760, filed on August 6, 1948, for Tacker. Said staple magazine includes means to mount a staple strip, and means to push it forwardly to a throat 72 located at the forward end of the staple magazine and below the grooves 53, so that the driver blade may press the forwardmost staple in the staple strip down through said throat 72. The staple magazine may include a removable pusher actuated by mechanism 73 received within the cut outs 27 at the rear end of the body, all as disclosed in said copending application Serial No. 42,760.

The handle 12 comprises a top wall 80 from which extend downwardly side flanges 81. The side walls 81 have openings through which the pivot pin 13 passes. On the pivot pin 13 is a coil torsion spring 82 having one arm 83 contacting the underside of the top wall of the handle, and a second arm 84 contacting the top stop 57. The coil torsion spring 82 normally tends to raise the handle so that the front edge 85 of the top wall of the handle contacts the upper edge 86 of the front wall 46 of the nose piece for limiting the upward movement of the handle.

The bracket 14 comprises a top wall 87 riveted

by rivet 88 to the underside of the top wall 80. Extending downwardly from the top wall 80 are side walls 89 carrying the transverse pivot pin 16 to which the upper end of link 15 is pivoted. The link 15 comprises parallel portions 90 (Fig. 3), interconnected at the top by a transverse portion 91. Disposed about the pivot pin 16 is a coil torsion spring 92 having one arm 93 (Fig. 1) engaging the top portion 91 of the link, and a second arm 94 hooked to one of the side walls 89. The coil torsion spring thus tends to rotate the link 15 in a clockwise direction, looking at Fig. 1 of the drawing.

The pivot pin 18 is carried by the lower ends of the arms 90 of the link 15. The trigger 17 comprises a top web portion 96 (Fig. 1) from which extend downwardly parallel side walls 99. Extending from walls 99 are apertured ears 100 through which the pivot pin 18 passes. The side walls 99 are formed with longitudinal slots 101 having at their rear ends upwardly offset portions 102 (Fig. 6). Said side walls 99 have front downwardly and rearwardly curved forward edges 103 and top forwardly and downwardly inclined edges 104. The side walls 99 straddle the plunger and are located adjacent the outer surfaces of the side walls 63 of said plunger. In the normal position shown in Fig. 1 the forward ends of the side walls 99 are located below the lower edges 69 of the outwardly pressed lugs 68 on the side walls of the plunger. Furthermore, the coil torsion spring 92 tending to rotate the link 15 in a clockwise direction also slides the trigger 17 downwardly and forwardly to bring the transverse pin 41 to the rear offset ends 102 of the slots 101.

The side walls 21 of the body members 20 are formed with outwardly pressed stop portions 105 having horizontal upper edges 106. These stop members serve to limit downward movement of the handle 12. When the lower edges 107 of the side walls 81 of said handle contact the edges 106 of the stop members 105, downward rotation of the handle is stopped.

The operation of the device will now be described. Beginning with the parts as shown in Fig. 1, upon depressing the handle 12 downwardly from the position shown in Fig. 1 to the position shown in Fig. 5, the forward ends of the edges 104 engaging the underedges 69 of the lug 68 will raise the plunger 19 and compress the spring 67, bringing the trigger to the position shown in Fig. 5. At this point the side walls of the handle have not yet reached the stop members 105. Further downward squeezing movement of the handle 12 will cause the trigger 17 to slide rearwardly bringing the pin 41 to the forward ends of the slot. During this motion the forward ends 104 of the side walls 99 of the trigger snap off the lug 68 and permit the compressed spring 67 to move the plunger downwardly for driving a staple.

It will be noted that the trigger remains up as the handle is squeezed to the point where the plunger is released. If the handle is thereafter released the driver spring 82 will lift the handle, and as the handle is lifted the coil torsion spring 92 tends to move the trigger 17 forwardly again, but during such action the forward cammed or curved edges 103 of the side walls 99 engaging the lugs 68 will push back the trigger until the forward end of the trigger bypasses the lugs.

The released position of the plunger with the handle still squeezed down is shown in Fig. 6.

It will be noted that when the trigger is moved

forwardly as shown in Fig. 1, the pivot pin 41 is in the upwardly offset portion 102 of the slot 101. Thus the trigger is held in its forward position as it rotates about the pivot pin 41, until it passes the critical angle where it is pulled downwardly and rearwardly, and in such position the pin 41 no longer occupies the offset portion 102 but is then disposed in the forward ends of the slots 101.

10 It will thus be seen that there is provided a device in which the several objects of this invention are achieved and which is well adapted to meet the conditions of practical use.

As various possible embodiments might be made 15 of the above invention, and as various changes might be made in the embodiment above set forth, it is to be understood that all matter herein set forth or shown in the accompanying drawings is to be interpreted as illustrative and not in 20 a limiting sense.

Having thus described my invention I claim as new and desire to secure by Letters Patent:

1. A tacker comprising a body, a plunger 25 slideable in said body, spring means to depress the plunger, a handle mounted on the body for movement in opposite directions and being movable by hand pressure, relative to the body in one direction, spring means to move said handle relative to the body in the opposite direction, a 30 trigger having a pivotal pin and slot connection with the body at an intermediate portion of the trigger, means including a link interconnecting the rear end of the trigger with the handle and means on the plunger disengageably engageable by the forward end of the trigger upon moving said handle in said first direction to raise said plunger against said spring means, and to pull said trigger out of engagement with respect to said plunger when said plunger is raised a pre-determined distance so that the plunger descends due to pressure of its spring means.

2. The combination of claim 1 in combination with spring means to rotate the link relative to the handle in a direction for moving the trigger forwardly of the body.

3. The combination of claim 2 in which the slot for the pin forming the pivotal connection for said trigger has an upwardly offset rear end portion.

4. A stapler comprising a body, a spring driven plunger movably disposed in the body for up and down sliding movement, a depressible handle pivoted to the body, a spring means for raising the handle, a bracket attached to the underside of the handle, a link pivoted at its upper end to the bracket and movable downwardly upon depression of the handle, a torsion spring for rotating the link relative to the bracket, a trigger pivoted at its rear end to the lower end of the link, a transverse fixed pin within the body rearwardly of the plunger, said trigger being formed with a slot between the ends thereof through which said pin passes, said trigger having rearwardly slidably engagement therewith upon depressing the handle, and said plunger being formed with a lug engageable at its underside by the forward end of the trigger, said trigger being urged forwardly into engaging position by said torsion spring whereby the plunger will be raised and the trigger slidably moved rearwardly to abruptly release the plunger upon depression of said handle.

5. A stapler comprising a body, a spring driven plunger movably disposed in the body for up and down sliding movement, a depressible handle

pivoted to the body, spring means for raising the handle, a bracket attached to the underside of the handle, a link pivoted at its upper end to the bracket and movable downwardly upon depression of the handle, a torsion spring for rotating the link relative to the bracket, a trigger pivoted at its rear end to the lower end of the link, a transverse fixed pin within the body, rearwardly of the plunger, said trigger being formed with a slot between the ends thereof through which said pin passes, said trigger having rearwardly slidable engagement therewith upon depressing the handle, and said plunger being formed with a lug engageable by the forward end of the trigger, said trigger being urged forwardly into engaging position by said torsion spring whereby the plunger will be raised and the trigger slidedly moved rearwardly to abruptly release the plunger upon depression of said handle, said trigger having curved front edges adapted to engage said lugs when the handle is raised for pushing the trigger rearwardly relative to the transverse pin to pass by the lugs for reengagement therewith.

6. A stapler comprising a body, a spring driven plunger slidably mounted therein for up and down movement, a depressible handle pivoted to the body, spring means to raise the handle, a bracket attached to the underside of the handle, a pivot pin fixed within the body rearwardly of the plunger, a trigger formed with an intermediate longitudinal slot through which said pivot pin passes, said trigger having rearwardly slidable engagement therewith upon depressing the handle, a link interconnecting said bracket with the rear end of the trigger and pivoted to said bracket and trigger, means on the plunger engageable by the forward end of said trigger upon depressing the handle, and spring means tending to push the trigger forwardly so that the rear end of the slot engages said pivot pin, whereby depression of said handle will raise the plunger and retract the trigger to abruptly release the plunger, and whereby upon raising of said handle, said spring means and said slot will permit the trigger to pass by the engageable means on the plunger for reengaging therewith.

7. A stapler comprising a body, a spring driven plunger slidably mounted therein, a depressible handle pivoted to the body, spring means to raise the handle, a bracket attached to the underside of the handle, a pivot pin fixed within the body, a trigger formed with a longitudinal slot through which said pivot pin passes, said trigger having slidable engagement therewith, a link interconnecting said bracket with the rear end of the trigger and pivoted to said bracket and trigger, hook means on the plunger engageable by the forward end of said trigger upon depressing said handle, and spring means tending to push the trigger forwardly so that the rear end of the slot engages said pivot pin, said slot having an upwardly offset rear end portion to receive and pivotally engage the pivot pin during initial depression of said handle, whereby depression of said handle will raise the plunger and slide the trigger rearwardly to abruptly release the plunger, and upon raising of the handle said spring means and said slot will permit said trigger to pass by said engageable means of said plunger for reengagement therewith.

8. The combination of claim 7, said trigger having a rearwardly curved front end to engage said hook means for camming the trigger rearwardly when the handle is raised.

9. A stapler comprising a body, a spring driven plunger slidably mounted therein for up and down movement, a depressible handle pivoted to the body, spring means to raise the handle, a bracket attached to the underside of the handle, a pivot pin fixed within the body rearwardly of the plunger, a trigger formed with an intermediate longitudinal slot through which said pivot pin passes, said trigger having rearwardly slidable engagement upon depressing the handle, a link interconnecting said bracket with the rear end of the trigger and pivoted to said bracket and trigger, means on the plunger engageable by the forward end of said trigger upon depressing the handle, and spring means tending to push the trigger forwardly so that the rear end of the slot engages said pivot pin, whereby depression of said handle will raise the plunger and retract the trigger to abruptly release the plunger, and whereby upon raising of said handle, said spring means and said slot will permit the trigger to pass by the engageable means on the plunger for reengaging therewith, said last mentioned spring means comprising a torsion spring about the pivotal connection between the link and the bracket, said torsion spring having one arm engaging the bracket and one arm engaging the link and tending to rotate the lower end of the link forwardly.

10. A stapling device comprising a body having side walls, a depressible handle pivoted at its forward end to the upper front end of the body, spring means tending to raise the handle, a plunger slidably mounted for vertical movement between said side walls, spring means to press the plunger downwardly, said side walls being interconnected by a transverse fixed pivot pin, a trigger having a top web and downwardly extending side walls, the front ends of which straddle the plunger, raised lugs on said plunger adapted to be engaged by the upper edges of said front ends of said side walls of the trigger, said side walls of said trigger being formed with slots through which said pivot pin passes having slidable engagement therewith upon depressing the handle, the rear ends of the side walls of the trigger being interconnected by a pin, a bracket attached to the underside of the handle and carrying a pin, and a link interconnecting the pin on the bracket with the pin at the rear end of the trigger, whereby depression of the handle will raise the plunger and abruptly release the same, and upon release of the handle, said last named spring means and said slots will permit said front ends of said trigger to pass by said lugs on said plunger for reengagement therewith.

11. A stapling device comprising a body having side walls, a depressible handle pivoted at its forward end to the upper front end of the body, spring means tending to raise the handle, a plunger slidably mounted for vertical movement between said side walls, spring means to press the plunger downwardly, said side walls being interconnected by a transverse fixed pivot pin, a trigger having a top web and downwardly extending side walls, the front ends of which straddle the plunger, raised lugs on said plunger adapted to be engaged by the upper edges of said front side of said side walls of the trigger, said side walls of said trigger being formed with slots through which said pivot pin passes having slidable engagement therewith upon depressing the handle, the rear ends of the side walls of the trigger being interconnected by a pin, a bracket attached to the underside of the handle and carrying a pin, and a link interconnecting

the pin on the bracket with the pin at the rear end of the trigger, whereby depression of the handle will raise the plunger and abruptly release the same and upon release of said handle, said last named spring means and said slots will permit said front ends of said trigger to pass by said lugs on said plunger for reengagement therewith, said link comprising a top interconnecting web disposed above the pin on the bracket, and arms extending downwardly therefrom and formed with openings through which the pin on the bracket and the pin at the rear end of the trigger pass.

12. The combination of claim 11 in combination with a coil torsion spring disposed about the pin on the bracket and having one arm engaging a portion of the bracket forwardly of the pin and another arm engaging the front edge of the interconnecting portion of the link.

13. A stapling device comprising a body having side walls, a depressible handle pivoted at its forward end to the upper front end of the body, spring means tending to raise the handle, a plunger slidably mounted for vertical movement between said side walls, spring means to press the plunger downwardly, said side walls being interconnected by a transverse fixed pivot pin, a trigger having a top web and downwardly extending side walls, the front ends of which straddle the plunger, raised lugs on said plunger adapted to be engaged by the upper edges of said front side of said side walls of the trigger,

said side walls of said trigger being formed with slots through which said pivot pin passes having sliding engagement therewith upon depressing the handle, the rear ends of the side walls of the trigger being interconnected by a pin, a bracket attached to the underside of the handle and carrying a pin, and a link interconnecting the pin on the bracket with the pin at the rear end of the trigger, whereby depression of said handle will raise the plunger and abruptly release the same and upon release of said handle, said last named spring means and said slots will permit said front ends of said trigger to pass by said lugs on said plunger for reengagement therewith, said slots having upwardly offset rear end portions adapted to receive and pivotally engage said pivot pin.

14. The combination of claim 13, the side walls of said trigger having downwardly and rearwardly curved front edges to engage the rear sides of said lugs for camming said trigger rearwardly, and upper rearwardly and upwardly inclined edges engaging the undersides of said lugs.

FRANK S. BOROUGH.
